UNITED STATES PATENT OFFICE.

PHILIPP A. RUPPELT, OF STEAMBOAT ROCK, IOWA.

CLOTHES-POUNDER.

1,107,707.

Specification of Letters Patent. Patented Aug. 18, 1914.

Application filed September 23, 1913. Serial No. 791,263.

To all whom it may concern:

Be it known that I, PHILIPP A. RUPPELT, a citizen of the United States, residing at Steamboat Rock, in the county of Hardin 5 and State of Iowa, have invented certain new and useful Improvements in Clothes-Pounders, of which the following is a specification.

My invention relates to improvements in 10 clothes pounders, the object of the invention being to provide a pounder which will operate through the action of air both on the downward stroke and on the upward stroke to thoroughly cleanse the clothes.

15 A further object is to provide an improved clothes pounder which may be taken apart and packed in a small space, and which is especially designed for use by enlisted men in the navy and others who have 20 but relatively small storage space.

With these and other objects in view, the invention consists in certain novel features of construction and combinations and arrangements of parts as will be more fully 25 hereinafter described and pointed out in the claim.

In the accompanying drawings: Figure 1 is a view in elevation illustrating my improvements. Fig. 2 is a view in vertical section. Fig. 3 is a view in section on an enlarged scale on the line 3—3 of Fig. 2. Fig. 4 is a top view of the lower cup member detached. Fig. 5 is a bottom plan view, and Fig. 6 is a perspective view of the valve 8.

30 My improved clothes pounder comprises two cups 1 and 2, the former located above and surrounding the upper portion of cup 1. This cup 1 is provided with diagonal partitions 3 dividing the cup into a plurality of 35 chambers, and each of these chambers communicates with the interior of the upper cup 2 through the medium of an opening 4 in the top of the cup 1. In other words, the cup 1 has a plurality of openings 4 in the top, so 40 that the air is free to circulate through the cup 1 into cup 2. Around the outside of cup 1, ribs 5 are fixed and serve to space the peripheries of the cups 1 and 2 apart, so that 45 the air and water is free to circulate between 50 the cups.

A screw-threaded plug 6 is provided on the lower cup 1 at its center, and said plug 7 is adapted to screw into a threaded socket 7 fixed to the inner face of cup 2 at the center 55 of the latter, so that this plug 6 and socket

7 constitute the coupling means between the cups and permits the cups to be readily separated when the pounder is to be packed away.

On the top of cup 2, preferably at one side 60 thereof, I provide a valve 8 which is movable in a valve chamber 9, and is confined by a screw-threaded cap 10. This cap 10 has an opening 11 therein through which the stem 12 of valve 8 projects. The stem 12 extends 65 at both sides of the valve and also projects through an opening 13 in a perforated partition 14 in valve casing 9. When the pounder is forced downwardly through the water, the valve 8 will move up against the 70 cap 10, and prevent any passage of air through the top of cup 2, but as the pounder reaches its upward stroke, the valve will move in the opposite direction, so that air 75 will rush in and relieve the suction which would otherwise occur.

A screw threaded socket piece 15 is secured to the top of the cup 2 at the center thereof, and is adapted to receive the screw-threaded end 16 of a handle 17, and this 80 handle may be removed when the pounder is not in use.

Various slight changes might be made in the general form and arrangement of parts 85 described without departing from my invention, and hence I do not limit myself to the precise details set forth, but consider myself at liberty to make such changes and alterations as fairly fall within the spirit and scope of the appended claim. 90

Having thus described my invention, what I claim as new and desire to secure by Letters Patent is:

A clothes pounder comprising a lower cup, an upper cup inclosing the upper portion of the lower cup and spaced from the top thereof, webs extending longitudinally of the lower cup and spacing the walls of the cups apart, said lower cup having a plurality of openings in its top and said upper 100 cup having a single valved opening in its top, substantially as described.

In testimony whereof I have signed my name to this specification in the presence of two subscribing witnesses.

PHILIPP A. RUPPELT.

Witnesses:

JOHN CRAMER,
HENRY CRAMER.
